UNITED STATES PATENT OFFICE.

JOHN R. GRUNDY, OF PHILADELPHIA, PENNSYLVANIA.

BRUSH.

SPECIFICATION forming part of Letters Patent No. 718,341, dated January 13, 1903.

Application filed June 5, 1902. Serial No. 110,346. (No model.)

To all whom it may concern:

Be it known that I, JOHN R. GRUNDY, a citizen of the United States, residing in Philadelphia, Pennsylvania, have invented certain 5 Improvements in Brushes, of which the following is a specification.

My invention consists of an improved form of brush particularly designed to be made of horsehair, bristles, or similar material, having for its object the provision of a brush of improved construction which shall have prolonged durability and usefulness.

A further object is to provide a construction such that when the hairs of the brush 15 are worn out or injured this part of the device as a whole may be replaced by a new one, the handle being used for an indefinite time.

These objects I attain as hereinafter set 20 forth, reference being had to the accompanying drawings, in which—

Figure 1 is a side elevation of the head or removable portion of one of my improved brushes, showing it as it appears before insertion within the handle of the brush; and Fig. 2 is a side elevation, partly in section, 25 of one of my improved brushes, showing the construction of handle whereby the head portion is maintained in position.

30 In the above drawings, A represents the handle of the preferred form of my improved brush, there being in the end of this a depression or cavity a, from the bottom of which extends into the handle a second cavity a' of an elongated form and less in diameter than the first cavity. The head of the brush consists of two wires b, twisted tightly together and holding between their strands bodies of horsehair B, although it will be understood 35 that bristles or any other suitable material may be employed for this purpose. The hair is placed between the two parallel lengths of wire in a relatively thin layer, after which one end of the wire is rigidly held while the 40 other is twisted, and thereby made to firmly retain the hair or bristles in position. These latter are then bent forwardly and one end

of the twisted body b' of the wire is forcibly pushed into the cavities a and a' of the handle, being retained in position, if desired, by 50 means of rosin or other suitable substance. The forwardly-bent hairs or bristles are held in place by means of the edges of the cavity a, and owing to the twisted shape of the portion b' of the brush-head formed by the wires 55 b this is retained in position within the handle, so that it is practically impossible to remove it under ordinary conditions of use.

It is to be noted that my improved brush has no metallic portion exposed beyond the 60 end of its wooden handle, and may for this reason be employed around certain classes of machinery in which brushes of the above-described form could not safely be employed. It will be seen that fused material within the 65 cavity in the end of the handle is of such a nature as to firmly hold and maintain the twisted wires of the brush-head in position under all working conditions, and yet is of such a nature that after the bristles have been 70 come broken or worn out it is possible to remove the stub of the brush-head and replace it with a new head.

I claim as my invention—

The combination in a brush, of a handle, a 75 head portion formed of twisted wires having brush-forming material confined between them, said handle having within it a two-part cavity for the reception of said head portion, one part of said cavity receiving the 80 twisted wires and the second portion receiving and confining in position the brush-forming material held by said wires, and fusible material within the portion of the cavity for the twisted wires whereby the head portion 85 is held to the handle, substantially as described.

In testimony whereof I have signed my name to this specification in the presence of two subscribing witnesses.

JOHN R. GRUNDY.
